UNITED STATES PATENT OFFICE.

LUCENA M. MORDEN, OF WATERBURY, CONNECTICUT.

LOOSE-LEAF BINDER.

1,048,852.

Specification of Letters Patent. Patented Dec. 31, 1912.

Application filed April 28, 1911. Serial No. 623,813.

To all whom it may concern:

Be it known that I, LUCENA M. MORDEN, a citizen of the United States, residing at Waterbury, in the county of New Haven 5 and State of Connecticut, have invented certain new and useful Improvements in Loose-Leaf Binders, of which the following is a specification.

This invention relates to loose leaf binders, the object of the invention being to provide an improved binder of the class described having a plurality of sets of openable prongs or rings, all of which may be simultaneously opened or closed by the shifting of such prongs or rings toward or from each other, while either or all of the sets may be shifted independently relatively to the supporting member carrying the same, whereby a much more practicable device of this character is provided than heretofore, and which advantageous features are obtained in an extremely simple and inexpensive manner without sacrificing the durability, strength and practicability of the structure, and in which the prongs are, in the embodiment shown, carried by suitable base plates either directly interlocked with each other or connected through the medium of a longitudinally extending member or members, which also forms the means for connecting the several sets of prongs together to permit them to be simultaneously opened or closed.

In the drawings accompanying and forming part of this specification, Figure 1 illustrates a perspective view of one form of this improvement; Figs. 2 and 3 illustrate details thereof; Fig. 4 is a cross-sectional view thereof; Fig. 5 illustrates a somewhat different embodiment of the same improvement; Fig. 6 is an end view thereof; Fig. 7 illustrates a detail thereof; Fig. 8 is a perspective view illustrating a still different embodiment of the same improvement; Fig. 9 is an end view thereof; Fig. 10 is a perspective view illustrating another embodiment of the same improvement; and Fig. 11 is an end view thereof.

Similar characters of reference indicate 50 corresponding parts in the different figures of the drawings.

The ring supporting member in the present instance, in all the forms of the present improvement shown herein, comprises what may be considered a back member consisting 55 of a concave formed casing 2 having a pair of inturned longitudinally extending flanges or edges 3 and 4, although it is to be understood that this casing or supporting member may be inclosed in a separate back member 60 which may be more readily attached in some instances to the covers if preferred. Each set of prongs 5 comprises a pair of similarly formed members, except that the prongs have the mating ends thereof formed 65 one with a notch while the other is formed to extend into such notch, although other forms of mating ends could be used if desired. Each set of prongs will be provided with a top or cover member 6 adapted to 70 overlap the supporting member and inclose the base members and prongs, this cover member being provided with a pair of recesses or notches to permit the opening and closing movement of the prongs. 75

In the form shown in Figs. 1 to 4 each prong is provided with a base plate 7, one of which is provided with oppositely extending projections or tongues 8 and 9, thus forming a notch for the reception of a centrally located member shown in the present instance as a bar 10 bent upon itself to form a groove 11, into which the edge of the base plate of the opposite prong fits, such edge thus forming a seat for the groove or slot 11, from 85 which it will be observed that in this form one of the base plates, by reason of its projections, overlaps such bar while the other base plate projects thereinto, the outer edges of each base plate being received under the 90 inturned flange of the supporting casing, and therefore these base plates constitute the means, together with the back member, for giving the desired spring action to the prongs so that they will properly close and 95 be held closed, or be held open when opened. The bar 10 thus connects all of the sets of prongs together so that by manipulating any one of the sets all of such sets will be simultaneously opened or closed in a manner 100 which will be readily understood, while at the same time any one of the sets may be

shifted or adjusted lengthwise of the supporting member toward or from a companion set of prongs or rings. It will also be observed that both prongs of each set 5 open substantially equally, so that a greater number of sheets may be inserted than when only one is opened while the other remains stationary, because a much larger opening is obtained between the mating ends of the 10 prongs.

In the form shown in Figs. 5, 6 and 7, the base plates of the prongs project under the inturned flange of the casing support in the manner hereinbefore described, but the 15 connecting bar 15 for the several sets of prongs extends through openings 16 formed by projecting or bulging the metal of one of the base plates of each set of prongs, while the two base plates are interconnected 20 by forming the opposed edges thereof with recesses 17 and projections 18, so that on opening or closing any one of the sets of prongs all of the prongs are simultaneously 25 opened or closed, while any or all of the sets of prongs may be shifted or adjusted lengthwise of the supporting member toward or from a companion set or sets thereof.

In the embodiment shown in Figs. 8 and 9 the base plates or members of each set of 30 prongs are received in longitudinally extending grooves or recesses 19 of a pair of lengthwise extending bars 20 and 21, which bars in turn are interconnected by a series of recesses 22 and projections 23. In this 35 form of the improvement it will be observed that each prong has its outer side notched or grooved, as at 24, for the reception of the inturned edge of the casing support, whereby each set of prongs will be 40 guided not only by the longitudinally extending bars, but also by the flanges of the casing support, and whereby also the desired spring action is imparted from the back or supporting member to the prongs.

In the embodiment shown in Figs. 10 and 11 the base plates 25 and 26, which are shown as somewhat curved so that the upper sides thereof are of convex formation, have their meeting faces interlocked by projections 27 and recesses 28, the projections of 45 each base plate, however, fitting into a groove 29 located at the inner edge of a longitudinally extending bar, two of which, as 30 and 31, are shown, although obviously 50 this could be reversed and the groove formed in the inner edge of each base plate for the reception of an inner edge of one of the longitudinally extending bars. The outer edge of each of the longitudinally extending bars is located under the inturned flange of the casing support, while the outer edge of each base plate is provided with a groove 32 into which the inner edge of the 55 inturned flange of the casing support fits. Obviously this groove might be formed in

the edge of the flange for the reception of the outer edge of the base plate, although the present construction is considered to be the simplest and least expensive, since it does not require the flange to be of any considerable thickness.

In all of these forms of the improvement it will be observed that both prongs of each set are opened or closed simultaneously, the prongs of each set having a movement toward and from each other, and that on the opening or closing of one set, by reason of the longitudinally extending bar or bars, all of the prongs of the companion sets are opened or closed also, and that one or all of the sets of prongs may be shifted or adjusted independently of the companion sets of prongs so as to properly locate them relatively to the openings in the sheets should the distance between the same vary, as they frequently do, and also to permit the use of shorter or longer leaves as occasion may require.

From the foregoing it will be observed that in some forms of the improvement the base plates are directly interlocked and so form a toggle joint between the prongs, while in other forms of the improvement the base plates are spaced apart, the toggle connection being formed by a longitudinally extending bar or bars constituting the connecting and guiding means between the several sets of prongs, and that the several sets of prongs are guided by the inturned edges or flanges of the back and also by a longitudinally extending member or bar or bars, and in the present improvement the prongs are shown of arch formation and preferably carried by suitably formed base plates which may or may not be directly interlocked.

Of course it will be understood that the various details may be more or less modified without departing from the scope or spirit of the present improvement. For instance, the rings or prongs may be formed of different kinds of stock, that is, they may be either of round or flat formation as may be preferred in practice, while the bars in some forms of the improvement may be made of wire and the grooves formed in the base of the prongs instead of in the bars, as hereinbefore stated, all of which, however, is within the purview of my improvement, as well as any other details and changes in construction which may be found desirable in practice in order to lessen the expense or simplify the improvement.

I claim as my invention:

1. A loose leaf binder comprising a plurality of sets of leaf receiving rings, each set comprising a pair of movable prongs both openable and closable simultaneously, means for supporting one or more sets of said rings for shiftable movement length-

wise of such supporting means, and means for connecting the several sets of prongs whereby on the opening or closing of any one of the sets all of the sets will be simultaneously opened or closed.

2. A loose leaf binder comprising a plurality of sets of leaf receiving rings, each set comprising a pair of movable prongs both openable and closable simultaneously, means for supporting one or more sets of said rings for shiftable movement lengthwise of such supporting means, means for connecting the several sets of prongs whereby on the opening or closing of any one of the sets all of the sets will be simultaneously opened or closed, and a top plate shiftable with each set of prongs.

3. A loose leaf binder comprising a plurality of sets of leaf receiving rings, each set comprising a pair of movable prongs both openable and closable simultaneously, means for supporting said rings for shiftable movement lengthwise of such supporting means, and means for inter-connecting the sets whereby on the opening or closing of any one of the sets all of the sets will be simultaneously opened or closed.

4. A loose leaf binder comprising a plurality of sets of leaf receiving rings, each set comprising a pair of movable prongs both openable and closable simultaneously, means for supporting said rings for shiftable movement lengthwise of such supporting means, means for connecting the prongs whereby on the opening or closing of any one of the sets all of the sets will be simultaneously opened or closed, and a slotted top plate shiftable with each set of prongs.

5. A loose leaf binder comprising a plurality of sets of leaf receiving rings, each set comprising a pair of movable prongs both openable and closable simultaneously, means for supporting the sets of rings some for shiftable movement lengthwise of such supporting means, and lengthwise extending means for connecting the several sets of prongs whereby on the opening or closing of any one of the sets all of the sets will be simultaneously opened or closed.

50 6. A loose leaf binder comprising a plurality of sets of leaf receiving rings, each set comprising a pair of movable prongs both openable and closable simultaneously, means for supporting the sets of rings some 55 for shiftable movement lengthwise of such supporting means, each of said prongs having a base plate and said prongs having connecting means therebetween whereby on the opening or closing of any one of the sets all 60 of the sets will be simultaneously opened or closed.

7. A loose leaf binder comprising a plurality of sets of leaf receiving rings, each set comprising a pair of movable prongs both openable and closable simultaneously,

means for supporting said prongs whereby some or all are shiftable lengthwise of such supporting means, each set of prongs having a toggle connection therebetween, and means for connecting the several sets of prongs whereby on the opening or closing of any one of the sets all of the sets will be simultaneously opened or closed. 70

8. A loose leaf binder comprising a plurality of sets of leaf receiving rings, each set comprising a pair of movable prongs both openable and closable simultaneously, means for supporting said prongs for shiftable movement lengthwise of such supporting means, each of said sets of prongs having interlocked base plates, and means cooperating with the base plates for connecting the several sets of prongs whereby on the opening or closing of any one of the sets all of the sets will be simultaneously opened or closed. 85

9. A loose leaf binder comprising a plurality of sets of leaf receiving rings, each set comprising a pair of movable prongs both openable and closable simultaneously, means for supporting said prongs for shiftable movement lengthwise of such supporting means, each of said sets of prongs having interlocked base plates, and means coöperating with the base plates for connecting the several sets of prongs whereby on the opening or closing of any one of the sets all of the sets will be simultaneously opened or closed, said means comprising a pair of lengthwise extending members. 90 95 100

115
11. A loose leaf binder comprising a plurality of sets of leaf receiving rings, each set comprising a pair of movable prongs both openable and closable simultaneously, a back member having inturned flanges for supporting said prongs for shiftable movement lengthwise thereof, each set of said prongs having base plates coöperating with said inturned flanges, and lengthwise extending members carried by said back member and coöperating with said base plates and connecting the several sets of prongs together whereby on the opening or closing of any of the sets all of the sets will be simultaneously opened or closed. 120
125
130

12. A loose leaf binder comprising a plurality of sets of leaf receiving rings, each set comprising a pair of movable arch-shaped prongs both openable and closable simultaneously, a back member having a pair of longitudinally extending inturned flanges, each set of said prongs having a pair of base plates engaged by the flanges of said back member, said base plates being interlocked, 5 a pair of longitudinally extending members connecting the several sets of prongs whereby on the opening or closing of any one of the sets all of the sets will be simultaneously opened or closed, said longitudinally extending members having their outer edges located under the flanges of the back member and their inner edges in engagement 10 with parts of said base plates.

13. A loose leaf binder comprising a plurality of sets of leaf receiving rings, each set comprising a pair of movable prongs both openable and closable simultaneously, means for supporting said prongs for shiftable movement lengthwise of such supporting means, and a plurality of longitudinally extending members connecting the several sets of prongs whereby on the opening or closing of any one of the sets all of the sets will be simultaneously opened or closed. 20

14. A loose leaf binder comprising a plurality of sets of leaf receiving rings, each set comprising a pair of movable prongs both openable and closable simultaneously, means for supporting said prongs for shiftable movement lengthwise of such supporting means, and longitudinally extending means connecting the several sets of prongs whereby on the opening or closing of any one of the sets all of the sets will be simultaneously opened or closed. 25

15. A loose leaf binder comprising a plurality of sets of leaf receiving rings, each set comprising a pair of movable prongs both openable and closable simultaneously, means for supporting said prongs for shiftable movement lengthwise of such supporting means, and longitudinally extending means connecting the several sets of prongs whereby on the opening or closing of any one of the sets all of the sets will be simultaneously opened or closed. 30

16. A loose leaf binder comprising a plurality of sets of leaf receiving rings, each set comprising a pair of movable prongs both openable and closable simultaneously, each prong having a base plate, means for supporting said prongs for shiftable movement lengthwise of such supporting means, and means connecting the base plates of the several sets of prongs along adjacent parts thereof whereby on the opening or closing of any one of the sets all of the sets will be simultaneously opened or closed. 45

17. A loose leaf binder comprising a plurality of sets of leaf receiving rings, each set comprising a pair of movable prongs both openable and closable simultaneously, each prong having a base plate, means for supporting said prongs for shiftable movement lengthwise of such supporting means and comprising a back member having inturned flanges, and means connecting the base plates of the several sets of prongs along adjacent 50

parts thereof whereby on the opening or closing of any one of the sets all of the sets will be simultaneously opened or closed, and comprising longitudinally extending means. 85

18. A loose leaf binder comprising a plurality of sets of leaf receiving rings, each set comprising a pair of movable prongs both openable and closable simultaneously, each prong having a base plate, means for supporting said prongs for shiftable movement lengthwise of such supporting means, and means connecting the base plates of the several sets of prongs along adjacent parts thereof whereby on the opening or closing of any one of the sets all of the sets will be simultaneously opened or closed, and comprising longitudinally extending means having means co-operating with the prongs. 70

19. A loose leaf binder comprising a plurality of sets of leaf receiving rings, each set comprising a pair of movable prongs both openable and closable simultaneously, means for supporting said prongs for shiftable movement lengthwise of such supporting means, and means for connecting the several sets of prongs whereby on the opening or closing of any one of the sets all of the sets will be simultaneously opened or closed, and comprising longitudinally extending means having guiding means for the prongs, each of said prongs having a base 80 plate co-operating with said guiding means. 90

20. In a loose leaf binder the combination with a series of separable binding loops or rings which are adjustable toward and away from one another, of means co-operating with said binding loops whereby the latter are simultaneously opened or closed. 100

21. In a loose leaf binder a base plate, a series of binding loops or rings on said base plate, which loops are adjustable toward and away from one another and means co-operating with said loops for simultaneously opening or closing the same. 110

22. In a loose leaf binder, the combination of a back plate, a plurality of pairs of pivotally supported arms carried by said plate and uniting to form rings, one arm of each pair having a notch and the other having a seat, and means located to engage said 120 125

notches and seats for simultaneously opening and closing the arms.

23. In a loose leaf binder, the combination of a back plate, a plurality of pairs of pivotally supported arms carried by said plate and uniting to form rings, said pairs adjustable toward and from each other, one arm of each pair having a notch and the other having a seat, and means located to engage said

notches and seats for simultaneously opening and closing the arms.

Signed at Waterbury, Connecticut, this 26th day of April, 1911.

LUCENA M. MORDEN.
